(57) **CLAIM**

The ornamental design for a low profile portable fitness trainer, substantially as shown and described.

DESCRIPTION

FIG. 1 is an isometric top left view of the low-profile portable fitness trainer;

FIG. 2 is an isometric bottom view of FIG. 1 thereof;

FIG. 3 is a top plan view thereof;

FIG. 4 is a left side elevational view thereof;

FIG. 5 is a right side elevational view thereof;

FIG. 6 is a bottom plan view thereof;

FIG. 7 is a front end elevational view thereof;

FIG. 8 is a rear end elevational view thereof;

FIG. 9 is an isometric top left view of an alternate position of a low-profile portable fitness trainer; and,

FIG. 10 is an isometric top left view of an alternate position of low-profile portable fitness trainer.

1 Claim, 10 Drawing Sheets
